Primary Examiner—Prabhakar G. Deshmukh
Attorney, Agent, or Firm—Quarles & Brady[57] **CLAIM**

The ornamental design for a glove, as shown and described.

DESCRIPTION

FIG. 1 is a front elevational view of a left hand glove showing my new design; shown in an unwrapped position; FIG. 2 is a rear elevational view thereof;

FIG. 3 is a right side top perspective view thereof; shown in a wrapped position;

FIG. 4 is a top plan view of FIG. 3;

FIG. 5 is a right side elevational view of FIG. 3;

FIG. 6 is a left side elevational view of FIG. 3;

FIG. 7 is a bottom plan view of FIG. 3;

FIG. 8 is a front elevational view of FIG. 3;

The corresponding views of a right hand glove of the first embodiment are similar to the views shown in FIGS. 1-8 inclusive;

FIG. 9 is a front elevational view of a left hand glove of a second embodiment showing my new design; shown in an unwrapped position;

The corresponding views of a second embodiment (FIG. 9) are similar to the views shown in FIGS. 2-8 inclusive with the exception of seams and stitching; the corresponding views of a right hand glove of a second embodiment (FIG. 9) are similar to the views shown in FIGS. 2-8 inclusive, with the exception of seams and stitching;

FIG. 10 is a front elevational view of a left hand glove of a third embodiment showing my new design; shown in an unwrapped position;

FIG. 11 is a rear elevational view of the glove of FIG. 10; The corresponding views of a left hand glove of a third embodiment (FIG. 10) are similar to the views shown in FIGS. 3-8 inclusive with the exception of seams and stitching; the corresponding views of a right hand glove of a third embodiment (FIG. 10) are similar to the views shown in FIGS. 10, 11 and 3-8 inclusive with the exception of seams and stitching;

FIG. 12 is a right side top perspective view of a right hand glove of a fourth embodiment showing my new design; shown in a wrapped position;

FIG. 13 is a top plan view of FIG. 12;

FIG. 14 is a left side elevational view of FIG. 12;

FIG. 15 is a right side elevational view of FIG. 12;

FIG. 16 is a bottom plan view of FIG. 12;

FIG. 17 is a front elevational view of FIG. 12;

FIG. 18 is a front elevational view of FIG. 12; shown in an unwrapped position;

FIG. 19 is a rear elevational view FIG. 18;

The corresponding views of a left hand glove of a fourth embodiment (FIG. 12) are similar to the views shown in FIGS. 12-19 inclusive;

FIG. 20 is a front elevational view of a right hand glove of a fifth embodiment showing my new design; shown in an unwrapped position; the corresponding views of a fifth embodiment (FIG. 20) are similar to the views shown in FIGS. 12-19 inclusive with the exception of the seams and stitching;

FIG. 21 is a rear elevational view of a left hand glove of a

sixth embodiment showing my new design; shown in an unwrapped position; and,

FIG. 22 is a rear elevational view of FIG. 21; the corresponding views of a right hand glove of a sixth embodiment (FIG. 21) in a wrapped position are similar to the views shown in FIGS. 12-17 inclusive; the corresponding views of a left hand glove of a sixth embodiment (FIG. 21) are similar to the views shown in FIGS. 12-17 inclusive;

The broken line showing of a hand is for illustrative purpose only and forms no part of the claimed invention.
